UNITED STATES PATENT OFFICE.

EDGAR A. GILLINDER, OF PHILADELPHIA, PENNSYLVANIA.

DESIGN FOR A LIGHTING GLOBE OR SHADE.

54,079.

Specification for Design.

Patented Nov. 4, 1919.

Application filed June 16, 1919. Serial No. 304,707. Term of patent 3½ years.

To all whom it may concern:

Be it known that I, EDGAR A. GILLINDER, a citizen of the United States, residing in the city and county of Philadelphia, State of Pennsylvania, have invented a new, original, and ornamental Design for Lighting Globes or Shades, of which the following is a specification, reference being had to the accompanying drawing, forming part thereof.

Figure 1 represents a bottom plan view of a lighting globe or shade showing my new design.

Fig. 2 represents a side elevation thereof.
I claim:—

The ornamental design for a lighting globe or shade as shown.

EDGAR A. GILLINDER.
